IGNITION COMPOSITION

Charles P. Spaeth, Woodbury, N. J., assignor to
 E. I. du Pont de Nemours & Company,
 Wilmington, Del., a corporation of Delaware

No Drawing. Application November 8, 1933,
 Serial No. 697,111

10 Claims.

(Cl. 52—4)

This invention relates to improved ignition compositions and more particularly to such compositions adapted for use as the top charge in electric blasting caps.

5 Ignition compositions of the type covered by this invention have numerous applications. For example, they may be used advantageously as the top charge in composition blasting caps, both of the ordinary fuse type, where the ignition charge 10 is fired by the spit of a fuse, and in electric blasting caps, in which the initiation of the ignition charge is brought about by means of the heat developed by the passage of an electric current through a bridge wire of very small diameter. A 15 second use is as the ignition charge in electric squibs, which are adapted to bring about the explosion of deflagrating explosives such as black powder, and which require an ignition charge developing a considerable flame. A third use is 20 in igniters generally, particularly those of the match head type. In this case, the ignition material may be cemented to the firing bridge wire by forming the ignition composition into a paste with various solvents. If so desired, the composition 25 may be subsequently coated and waterproofed by solutions of nitrocellulose.

Blasting caps of both the fuse and electric types, as commonly used, are of the class called composition caps, in that they contain more than 30 one explosive charge, for example a base or secondary charge at the closed end of the metal shell container and a primary charge superimposed on the secondary charge. As secondary 35 detonating compounds, tetrannitromethylaniline (tetryl), trinitrotoluene, pentaerythrite tetrinitrate, picric acid, diazodinitrophenol and the like have been most commonly used, while the primary charges have customarily comprised mercury fulminate, either alone or mixed with an 40 oxidizing agent such as potassium chlorate, and lead azide. The use of either mercury fulminate or lead azide in metal shells at times involves certain disadvantages due to the action of these materials on the shell wall. Lead azide for example, can not be used in open copper shells because of the formation of supersensitive copper 45 azide. Mercury fulminate, on the other hand, is not desirable for use in similar shells of aluminum 50 because of the usual presence of small amounts of free mercury in the material, which tends to form amalgams with the metal and thus disintegrate it.

When lead azide alone is employed as the primary charge, difficulty is frequently met in the

ignition of this material, so that it is necessary to use an additional ignition charge. As such a charge, mixtures of lead sulfocyanate with oxidizing agents and fuels have been used, as well as lead hypophosphite compositions, nitrocellulose by itself, and many other compositions, both in loose and compressed form.

The object of my invention is a new and improved ignition composition having highly desirable properties. A further object is a composition that is compatible for use with the materials ordinarily employed for cap shells. A still further object is a composition well adapted for ignition by electrical means because of its low firing current requirements. Additional objects will be disclosed as the invention is further described.

I have found that the foregoing objects are accomplished by the use, as an ignition composition, of nitro-cellulose impregnated with a liquid 20 explosive nitric ester. Various liquid nitric esters are suitable for the purpose intended, for example nitroglycerin, ethylene glycol dinitrate, nitrochlorhydrins, and the like. Preferably, however, I employ nitroglycerin as the liquid nitric 25 ester, because of its favorable properties and its availability. Similarly, various kinds of nitrocellulose may be utilized as the material for impregnation. I prefer, however, to use nitrocotton, and particularly a nitrocotton in the form 30 of smokeless powder in comminuted condition. The material known as Pyro powder, in ground form, has been found to be very satisfactory for use.

The impregnated nitrocellulose material, by itself, gives an ignition composition that has desirable properties in many respects. It is not altogether satisfactory, however, from the point of view of speed of burning and firing current requirements, when intended for ignition 40 by electrical means. I prefer, therefore, to incorporate with the impregnated nitrocellulose an inorganic salt, preferably an oxidizing salt, for example sodium nitrate, sodium nitrite, potassium nitrate, potassium chlorate, potassium perchlorate and the like. Various non-oxidizing salts, however, may also be used, such as sodium chloride and potassium chloride. I find potassium chlorate to be the most desirable of the 45 inorganic materials mentioned.

Various compositions of the ingredients listed heretofore, may be used. Preferably, however, I employ a charge within the limits of 40-80% smokeless powder, 5-35% nitroglycerin and 55

2-25% potassium chlorate. As a suitable composition, I may cite the following:—

	Percent
5 Smokeless powder	63
5 Nitroglycerin	27
5 Potassium chlorate	10
	100

10 While the compositions, according to my invention, may be used as an ignition charge in ordinary fuse caps, they are not as satisfactory in such use as when ignited by electrical means, since in some cases they are not ignited with 15 sufficient ease by the spit of the fuse.

Various fields of use are at hand where ignition is brought about by electrical means and where the compositions, as described, possess great advantages. One preferred manner of use of the 20 ignition compositions, according to my invention, is as a top charge in electric blasting caps, either as the primary charge itself, without a special ignition charge, or as the ignition charge above the primary charge. When used as a primary 25 charge, my ignition composition will be superimposed on a base charge of tetryl or other suitable detonating compound. If desired, however, a base charge of any suitable material may be used, with a primary charge above, of lead azide 30 for example and a top ignition charge of the composition described in the foregoing. A charge consisting of 63% smokeless powder, 27% nitroglycerin, and 10% potassium chlorate, for example, is readily ignited by the hot bridge wire 35 of an electric blasting cap, requiring a firing current of only 0.358 amperes. In addition, such a composition possesses a relatively high initial velocity of combustion, so that it rapidly picks up to its maximum speed.

40 My impregnated smokeless powder charge is similarly adapted for use in electric squibs, where it gives very favorable results, since it is readily brought to ignition electrically by the bridge wire and possesses the flame producing qualities required in the case of squib compositions. For 45 similar reasons, such compositions are satisfactory as ignition charges for igniters of the match head type.

The compositions according to my invention 50 may be prepared in various ways. I have found an effective method of bringing about the desired results to comprise mixing Pyro powder with water in such a manner as to cause it to become thoroughly wet. Nitroglycerin is then added 55 slowly, while the suspension is agitated for several hours. I find a suitable ratio of the ingredients to be 150 parts by weight of Pyro powder, 675 parts of water and 66 parts of nitroglycerin. After the agitation of the ingredients in the manner described, the nitrocellulose becomes thoroughly impregnated with the nitroglycerin. The 60 impregnated nitrocotton is filtered on a suction filter to a moisture content of about 25%. At this time, the material is mixed with the inorganic salt, for example potassium chlorate, a suitable amount of the latter being 24 parts by weight. The water present in the material tends to dissolve the potassium chlorate, thereby bringing 65

about at least a partial impregnation with this salt, as well as with the nitroglycerin. The material, after being screened and dried is in a form suitable for loading into blasting caps. When dry, it is relatively free running, and has no tendency to be lumpy.

70 The ignition composition, prepared according to my invention possesses various features of novelty and many desirable properties. It makes possible the use of a sensitive liquid explosive ingredient in such compositions, without any of the disadvantages ordinarily associated with liquid ingredients under such use. The addition of the inorganic salt tends to give grains of higher density, better free-running properties, 15 and a composition of lower firing current requirements.

75 I have described my invention in considerable detail in the foregoing, but it will be understood that there may be many modifications in the proportion of the ingredients present and in the method of treatment, without departing from the scope of the invention. I intend to be limited, therefore, only by the following claims.

I claim:

25 1. An ignition composition comprising nitrocellulose impregnated with a liquid explosive nitric ester.

2. An ignition composition comprising nitrocellulose impregnated with nitroglycerin.

30 3. An ignition composition comprising nitrocellulose impregnated with a liquid explosive nitric ester, said impregnated material being intimately associated with an inorganic salt.

35 4. An ignition composition comprising nitrocellulose impregnated with a liquid explosive nitric ester and with an inorganic oxidizing material.

5. An ignition composition comprising nitrocellulose impregnated with nitroglycerin and with 40 potassium chlorate.

6. An ignition composition comprising comminuted smokeless powder, impregnated with nitroglycerin and with an inorganic oxidizing salt.

45 7. An ignition composition comprising smokeless powder impregnated with nitroglycerin and potassium chlorate, said charge comprising 40-80% smokeless powder, 5-35% nitroglycerin, and 2-25% potassium chlorate.

8. An ignition composition as the top charge 50 in a composition blasting cap, comprising smokeless powder impregnated with nitroglycerin and an inorganic oxidizing salt.

9. An ignition composition as the top charge in a composition electric blasting cap containing 55 a base charge of a secondary detonating compound, said ignition composition comprising smokeless powder impregnated with nitroglycerin and potassium chlorate and with an inorganic oxidizing salt.

10. An ignition composition as the top charge 60 in an electric blasting cap containing a base charge of a secondary detonating compound, said ignition composition comprising smokeless powder impregnated with nitroglycerin and potassium chlorate and having the composition 40 to 65 80% smokeless powder, 5 to 35% nitroglycerin, and 2 to 25% potassium chlorate.

CHARLES P. SPAETH.
